UNITED STATES PATENT OFFICE

ROBERT R. GOSHORN, OF JASONVILLE, INDIANA, ASSIGNOR TO THE ALL-WAYS-HOT MFG. CO., OF JASONVILLE, INDIANA

MAGNETIC LIQUID HEATER

Application filed March 24, 1928. Serial No. 264,502.

The present invention relates to electric or magnetic heaters of the type used for providing hot water for domestic purposes as well as for space heating in houses, apartments, etc. The invention is concerned more especially with improvements in connection with the heater disclosed in my copending application #213,855, filed August 16, 1927, and entitled "Magnetic liquid heater."

One of the objects of the invention resides in so constructing the apparatus and the piping immediately associated therewith as to eliminate dissipation of heat through spontaneous circulation of water exteriorly of the heater.

Another object of the invention consists in simplifying the construction of the previously disclosed heater with a consequent reduction in the initial cost thereof without sacrificing its efficiency or durability.

A further object of the invention resides in the use of a connection panel by means of which the primary coil of the transformer may be selectively tapped at different points so as to obtain the voltage and wattage most advantageous for the work to be done.

A still further object of the invention is found in the use of a fuse cartridge containing a metal of low melting point in contact with the secondary winding of the transformer and in the primary circuit to avoid overheating of the apparatus.

Other objects and advantages of the invention will be apparent from the following description when taken in connection with the accompanying drawings; in which

Figure 1 is a vertical section through the improved water heater.

Figure 2 is a horizontal section taken on line 2-2 of Figure 1; and

Figure 3 is a side elevation of a conventional type of a radiator with the present improvements installed therein; parts being broken away so as to show the interior construction.

Referring to the drawing more specifically the numeral 1 indicates the main body of the heater which is suitably mounted on any desired type of base or pedestal 2. The heater is preferably composed of inner and outer

metal jackets 3 and 4 spaced apart so as to receive the heat insulating material 5; and within the interior of the jacket 3 is a partition 6 which is preferably arched upwardly and serves to provide an upper tank compartment 7 and a lower compartment 8 for the reception of the heating unit which is generally indicated by the numeral 9.

The receptacle comprising the inner and outer jackets 3 and 4 and the heat insulating material 5 rest upon a base 10 which is of a diameter substantially the same as the diameter of the outer jacket 4 thereby forming a support for both of these jackets as well as for the heat insulating material 5 which is placed within the annular space between these jackets.

The heating unit 9 consists of a transformer which is secured to the base 10 by means of any suitable clips or fastening means 11. The core of the transformer consists of a closed laminated iron core 12 around which is placed the primary coils or windings 13. The secondary winding of the transformer is in the form of pipe coils 14 which have their terminals 15 and 16 provided with conventional pipe unions 17 and 18. Preferably the turns of these coils are provided with an insulating covering 14', such as cotton water hose. It will be noted that the primary coils 10 contain a great many turns of comparatively small high resistance wiring, while the secondary coils 14 are each composed of few turns of heavy low resistance tubing. This gives a high transformation ratio so that when alternating current at approximately 110 volts is supplied to the primary coils a very heavy current will flow in the low resistance secondary and will generate heat and raise the temperature within the tubing.

The bottom of the tank 7 is provided with an opening surrounded by a threaded boss 19 and in which is threaded a metal sleeve 20 extending from the bottom of the tank to a point adjacent its top. Positioned within the pipe or sleeve 20 and spaced therefrom is an extension tube 21 which is connected with the coil terminal 15 by means of pipe union 17. This tube 21, as stated, is spaced

from the inner wall of the sleeve 20 and is thus entirely out of contact with any portion of the tank. Within this space an annular packing of heat insulating material may be inserted if desired. To provide for the secondary circuit, however, the upper end of the tube 21 is welded or otherwise intimately connected with the upper end of the sleeve 20. A short pipe or tube 22 is threaded into the bottom of the tank 7 by means of a boss 23 and is connected with the second terminal of the pipe coils 14 by means of the union 18.

It will thus be observed that a closed circuit is provided for the secondary winding; 15. the current induced in the coils 14 flowing from terminal 15 upwardly through the tube 21, downwardly through the sleeve 20 to the bottom of the tank 7, and thence through the tank to the tube 22 and the coil terminal 16.

20. I will now describe that feature of the construction by which a heat seal is provided so as to eliminate the dissipation of heat from the tank by means of a spontaneous circulation of the water. It is, of course, a well known principle that heated liquids are lighter than cool liquids and will rise to the surface of any receptacle such as a tank or tube in which relatively hot and cold liquids are contained. It will be obvious, therefore, that 25 if a pipe or other conduit be attached at or near the top of a compartment containing heated liquid and extends upwardly therefrom, such heated liquids will naturally rise to the top of the pipe giving off their heat to the surrounding atmosphere, becoming thereby cooler and descending within the pipe as hotter liquids continue to rise to the surface. This action will naturally create a circulation of the water within the pipe and thereby greatly reduce the efficiency of any heater 30 thus constructed, because of this waste of heat.

To avoid this objectionable feature in liquid heaters I have provided what I term a 45 heat seal and which comprises a tube 24 which communicates with the upper end of the tank 7 and extends downwardly through the heat insulating material 5 to a point slightly below the base 10. Connected to the lower end of this tube 24 is a conduit 25 which will extend to the point at which the hot liquid is to be used and may either extend downwardly, upwardly, or in a horizontal direction, as occasion may warrant. In such a construction 50 it will be apparent that a spontaneous circulation of the heated liquid within the tube 24 is eliminated due to the fact that the tube communicates with the upper end of the tank 7 and then extends downwardly. Any hot 55 water passing into the tube 24 at the upper end of the tank 7 will remain in the upper end of the tube 24 and cannot cause a circulation of the fluid, except, of course, when the faucet or other dispensing means is turned 60 on to withdraw liquid from the heater.

While the tube 24 is shown as extending below the base 10 of the apparatus, it will be obvious that to produce the desired heat seal it is only necessary that the tube extend below the partition 6 which forms the bottom of the 70 liquid tank 7.

This heat seal is also provided in the conduit which carries cold water into the tank to be heated. This conduit comprises a tube 26 which extends from a point adjacent the 75 bottom of the tank 7 upwardly through the top thereof where it is connected by elbows 27 with the downwardly extending conduit 28 which also passes through the heat insulating material 5 to a point below the base 80 10 where it is connected to the main system of piping 29. This arrangement also prevents a spontaneous circulation of liquid due to the fact that any heated liquid rising in the pipe 26 will be halted in the upper end of the 85 pipe and while it is possible that a slight circulation of the liquid may occur within the pipe section 26 it will not cause any loss of heat whatever, inasmuch as this pipe is entirely situated within the tank itself. 90

From the above description of the secondary circuit and the conduit systems it will be apparent that the cool water entering the tube 22 is gradually heated as it passes through the coils 14, the temperature thereof increasing as the water passes upwardly through the tube 21 due to the fact that it has been longest exposed to the heat within the tubing. The annular space between the tube 21 and sleeve 20 also serves as an insulation 100 for these parts. Furthermore, the fact that the maximum temperature of the water is not reached until the water reaches a point adjacent the top of the tank 7, prevents serious defects and loss of efficiency in the heating 105 unit due to the fact that the primary windings are not unduly heated and also the fact that the use of heat insulating material about these parts is rendered unnecessary.

To automatically control the temperature 110 to which the water in the tank 7 is raised, I have provided a thermostat which comprises a tube 30 provided with an enlarged lower end 31 for the reception of ether or other voltaile fluid. This thermostat is fully disclosed in my co-pending application, Serial No 235,980, filed November 26, 1927, and it will suffice to say here that the end of the pocket 31 of the thermostat is located within the tank at a point intermediate the upper 115 and lower ends thereof. The purpose of so locating the thermostat being to permit it to be influenced by the mean temperature of the liquid within the tank rather than by the hotter liquid at the top of the tank or the relatively cold liquid at the bottom of the tank, thus tending to maintain the liquid in the tank at a more nearly even temperature. 120

The pipe coils 14 are provided with a drain connection 32 to which is attached a drain 125 130

cock 33 and it should be particularly noted that these connections extend substantially vertically downwardly and are without bends so as to permit a free drainage of the fluid 5 and thereby permit the ready removal of any sediment or other material which may be within the coils.

It is desirable that the present apparatus be so constructed as to permit its operation 10 over a wide range of voltage and wattage, and for this purpose I have provided a control panel 34. This panel carries a plurality of terminals 35 tapped to the primary windings at a variety of points, and for cooperation 15 with these terminals 35 I have provided a cross bar 36. It will thus be apparent that by placing the bar 36 across the proper pair of terminals 35 the desired amount of voltage and wattage may be readily selected. It is 20 also desirable to protect the apparatus from overheating and to this end I provide a fuse 37 which is electrically connected in the primary circuit and is in physical contact with the secondary circuit. This fuse 37 comprises 25 a cartridge containing a metal of low melting point which will promptly break the primary circuit as soon as the temperature of the metal is raised above its melting point.

To permit adjustments of the bar 36 to 30 procure the proper amount of current the body of the apparatus is provided with a door 38 hinged at 39 and provided with a latch 40.

In assembling the device as disclosed in 35 Figures 1 and 2 the heating unit 9 is first secured to the base plate 10 and the jackets 3, 4 and heat insulating material 5 then slipped over the heating unit and secured to the base 10 in any manner desired. The unions 17 and 18 are then connected to the pipes or tubes 40 21 and 22 and connections made to the mains 25 and 29. The apparatus is then ready for use, it being assumed that the primary of the transformer is connected up with the house circuit. By placing the inlet and outlet 45 tubes 28 and 24 within the heat insulating material 5 and extending them downwardly in the manner shown it will be apparent that I have provided a positive gravity heat seal which is so constructed that it would be impossible 50 for anyone to install the heater in such a way as to permit a spontaneous circulation of liquid within the tubing with a consequent dissipation or loss of heat.

In the operation of the device water in the 55 main pipe lines of the city is conveyed to the bottom of the tank through the pipes 29, 28, 27 and 26 automatically as heated water is withdrawn from the tank by means of the pipes 24 and 25. As this cold water leads into the tank and lowers the temperature adjacent the thermostat 31 the thermostat will operate a switch (not shown) to close the circuit through the primary coils 13 thus sup- 60 plying secondary current to the pipe coils

14 and tube 21 as hereinbefore described. The secondary current, of course, will gradually heat the water as it descends through the pipe terminal 16 and around the coils 14 and up through the terminal 15. The water passing 70 upwardly through the terminal 15 will have a temperature of about 100° to 120° F. and the maximum temperature of 170° F. or other temperature to which the thermostat is adjusted, will not be attained until the water 75 reaches the upper end of the tube 21.

It will thus be seen that the hottest water is at the upper end of the tank while the relatively cold water is at the lower end of the tank. This gradual heating of the water as 80 it passes upwardly through the tube 21 gives rise to convection currents within the tank 2 and thus tends to cause the water therein to intermingle so as to produce an even temperature. Furthermore, the fact that the maximum 85 temperature is created within the tube 21 has not only the advantage of avoiding undue heating of the primary coils and avoiding the use of heat insulation material about these parts, but also limits the deposit of lime 90 to the tube 21 rather than to the coil 14. This is of paramount importance in that the tube 21 may be readily scaled or cleaned by merely disconnecting the union 15, whereas cleaning of the pipe coils 14, if not entirely impossible, would at least require that the entire apparatus be dismounted and overhauled. 95

In the modified form of the construction shown in Figure 3 the heating unit, as hereinbefore described, is shown in combination 100 with a radiator such as employed in heating houses, apartments, and the like. In this embodiment of the invention the first few sections of the radiator 50 are shown as divided off so as to provide a compartment 51 for the heating unit which comprises the transformer 9 including the laminated core 12, primary winding 13, pipe coils 14, and coil terminals 15 and 16, as hereinbefore referred to. The coil terminals 15 and 16 are 105 connected by unions 17 and 18 to the tube 21 which is mounted within one of the radiator sections by means of the sleeve 20 and to a threaded boss 52 on the radiator. Any number of sections may be added to the radiator 50 and, of course, pipes may be connected to the top and bottom of the radiator and carried through a building to be attached to other radiators which will be heated 110 through the medium of the same heating element 9. In this construction a small expansion chamber or compartment 53 is associated with the upper end of the radiator and a drain 54 is connected with the bottom thereof. A control panel 34 with terminals 35 and cross bar 36 is employed in the heating unit of this construction in just the same manner as in the previously described embodiment of the invention, and a fuse 37 is 115 also incorporated and is connected in the 120

125 130

primary circuit and in physical contact with the secondary circuit for the purpose previously described. The compartment 51 in which the heating unit or transformer is mounted may be provided with a door 55 at the end or side thereof to permit ready access to the unit and a switch 56 is mounted on the exterior of the radiator in such position as to be readily accessible for opening or closing the circuit through the primary windings.

In this alternate form of construction all of the novel features of the form disclosed in Figures 1 and 2 are employed with the exception of the heat seal and the thermostat; it being apparent, of course, that a heat seal is not necessary or desirable where the device is to be used for space heating, but it will be understood that any conventional type of thermostat may be readily associated with the construction, as disclosed in this second embodiment of the invention.

From the foregoing description taken in connection with the accompanying drawings it will be noted that I have devised a simple and inexpensive type of electric heater of a unitary construction; that the parts of the apparatus are all entirely inclosed within and form a part of the tank or radiator construction; that a positive gravity heat seal is provided which eliminates loss of heat by spontaneous circulation of the fluid; that parts which much necessarily be heat insulated are so insulated at the time and place of construction of the apparatus; that the device is so designed as to cause a free circulation of water or other liquid within the tank or the radiator; that the deposit of lime is confined to such parts of the apparatus as may be readily removed and cleaned; that the parts are so constructed as to readily adapt the apparatus to use with any alternating electric current and over a widely varying range of voltage; that by reason of the unions 17 and 18 the heating unit may be readily disconnected from other parts of the apparatus for cleaning purposes or for repair; and that the entire apparatus is conveniently adapted for the employment of a thermostatic control.

In accordance with the patent statutes I have disclosed herein two of the preferred embodiments of the present invention, but it is to be understood that these disclosures are intended as illustrative of the invention rather than in any limiting sense, and as various minor changes and modifications may be made within the disclosed structures without departing from the spirit of the invention, I aim to include all such changes and modifications within the scope of the appended claims.

What I claim as new and desire to secure by Letters Patent is:

1. In a water heater, a tank, a transformer including a pipe coil as the secondary wind-

ing, a fuse in the primary circuit of the transformer, said fuse being in contact with a portion of the secondary winding.

2. In a water heater, a tank, a transformer including a pipe coil as the secondary winding, a fuse cartridge containing a metal of low melting point in the primary circuit, said fuse being in contact with the pipe coil.

3. In a water heater, a tank, a transformer including a primary winding, a pipe coil as the secondary winding, a control panel, means associated with said panel for tapping the primary winding at various points, a fuse mounted on said panel in the primary circuit, said fuse being in contact with the pipe coil.
